[57] **CLAIM**

The ornamental design for a tennis racquet, as shown and described.

DESCRIPTION

FIG. 1 is a front elevational view of a tennis racquet showing my new design, the undisclosed opposite side being identical;
 FIG. 2 is a side elevational view thereof, the undisclosed opposite side being identical;
 FIG. 3 is a front elevational view of a second embodiment of the tennis racquet as disclosed in FIG. 1;
 FIG. 4 is a side elevational view of FIG. 3;
 FIG. 5 is a cross sectional view taken on line 5—5 of FIGS. 1 and 3;
 FIG. 6 is a cross sectional view taken on line 6—6 of FIGS. 1 and 3;
 FIG. 7 is a cross sectional view taken on line 7—7 of FIGS. 1 and 3;
 FIG. 8 is a cross sectional view taken on line 8—8 of FIGS. 1 and 3;
 FIG. 9 is a cross sectional view taken on line 9—9 of FIGS. 1 and 3;
 FIG. 10 is a top plan view of FIG. 1;
 FIG. 11 is a bottom plan view of FIG. 1;
 FIG. 12 is a top plan view of FIG. 3; and,
 FIG. 13 is a bottom plan view of FIG. 3.
 The characteristic feature of the design resides in the substantially round shape of the head portion of the racket.
